UNITED STATES PATENT OFFICE.

JOHN S. SHANKS, OF CANTON, OHIO, ASSIGNOR TO THE CANTON CLOTHES DRYER COMPANY, OF STARK COUNTY, OHIO, A CORPORATION OF OHIO.

CLOTHES DRIER.

Application filed December 21, 1921. Serial No. 523,932.

To all whom it may concern:

Be it known that I, JOHN S. SHANKS, a citizen of the United States, residing at Canton, county of Stark, and State of Ohio, have invented certain new and useful Improvements in Clothes Driers, of which the following is a specification.

The invention relates to cabinets containing means for heating and circulating air in and through the cabinet for drying clothes and other articles therein; and the object of the improvement is to create a constant circulation of a large volume of uniformly heated air throughout the interior of the cabinet for quickly drying the contents without burning or discoloring the same.

Such a cabinet is preferably made with considerable height and width as compared to the depth, and when the same is heated by a gas burner or other intensive means, difficulty is experienced in overheating the cabinet in the region of the burner without sufficiently heating the remote portions thereof; and difficulty is also experienced in circulating the heated air throughout all portions of the cabinet.

The present invention involves the use of a radiator extending from end to end of the cabinet adjacent to the bottom thereof, a gas burner or other heating element in one end of the radiator, an air vent chamber below one end of the radiator receiving air from within the cabinet around the sides of the radiator and delivering it into the radiator below the burner, inlet openings for receiving air through the bottom of the cabinet directly below the remainder of the radiator and deflecting means for directing heated air from over the burner toward the other end of the cabinet.

The invention also involves the use of an outlet flue for the radiator having a relatively large cross area for the movement of a considerable volume of air, with inlet apertures in the side of the flue for automatically checking the flow of air from the cabinet.

The improvement also includes features of construction to permit the cabinet to be made in comparatively small separable parts for transportation, which can be readily assembled at the point of use by an individual

workman to form a strong and rigid case or shell.

A preferred embodiment of the invention, in which a gas burner is used as a heating element, is illustrated in the accompanying drawings forming part hereof, in which—

Figure 1 is a front elevation of the cabinet with one door open, showing articles hanging therein for drying;

Fig. 2, a right end elevation of the cabinet with both doors closed;

Fig. 3, an elevation section of the cabinet on line III—III, Figs. 1 and 4;

Fig. 4, an elevation section of the cabinet on line IV—IV, Figs. 2 and 3;

Fig. 5, a detached perspective view of the deflecting plate;

Fig. 6, a plan section on line VI—VI, Fig. 4; and

Fig. 7, a plan section on line VII—VII, Fig. 4.

Similar numerals refer to similar parts throughout the drawings.

The cabinet is preferably made of sheet metal with a base frame 10 carrying a bottom wall 11 at an interval above the supporting floor 12; end walls 13, back wall sections 14, a lower front wall section 15, upright door frame sections 16, front doors 17 above the front wall section, and a top frame 18 carrying a top wall 19.

The base 10 is preferably provided with an inturned flange 20 forming a footing resting upon the floor, and along the edges of the bottom 11 are shaped the rabbeted shoulders 21, which not only strengthen and stiffen the base in all directions but form a bearing for the upright walls. Series of apertures 22 are provided in the side walls of the base to admit a plentiful supply of air underneath the bottom wall of the cabinet; and series of apertures 23 are provided in the bottom wall to admit a plentiful supply of air into the cabinet underneath the radiator flue 24 therein. The series of apertures 23 does not extend under the air vent chamber 25 which is located under the radiator flue at one end of the cabinet.

The lower end of the upright walls rest upon the rabbeted shoulders 21 of the base, and the end and front walls may be secured thereon by means of angle pieces 26. The back wall sections 14 are preferably cor-

rugated so as to strengthen and stiffen the same. The top frame 18 is preferably provided with inset threefold flanges 27 forming sockets for receiving and resting upon the upper ends of the upright walls.

The inner edges of the upright door frame sections 16 are provided with L-flanges 28 engaging with corresponding socket flanges 29 on the end edges of the front wall section 15; and the outer edges of the door frame sections and of the corrugated back sections are provided with off-set flanges 30 fitting in box flanges 31 formed on the edges of the end walls 13.

15 The case formed by the cabinet is completed by the doors 17 which are hinged to the upright door sections, and the several parts of the cabinet when assembled are secured together by means of bolts or rivets. The 20 angular formation of the several joints and particularly the box flanges forming the corners of the cabinet, give the same great strength and rigidity.

The radiator flue 24 extends lengthwise 25 from end to end of the cabinet adjacent to the bottom thereof, and its dimensions are such as to leave a considerable interval for the passage of air between the flue and the back and front walls of the cabinet. A gas 30 burner 32 is located in the end of the flue which is above the air vent chamber 25; the gas burner illustrated being provided with an air mixing chamber 33 located outside the end of the cabinet through which gas is supplied by a pipe 34.

One or more air tubes 35 extend from the air vent chamber 25 upward into the radiator flue 24. These tubes are preferably aligned underneath the burner tube 32 and 40 serve to supply the same with the additional air required for completing the combustion of the gas which occurs within the radiator flue; which additional air is drawn from inside the cabinet through a series of apertures 45 36 in the top of the vent chamber on each side of the air tubes.

The other end of the radiator flue communicates through a tubular outlet 37 with the upright outlet flue 38 mounted outside 50 the end of the cabinet; and the upright flue may be surrounded by a shielding jacket 39 which is preferably open at its upper and lower ends.

The upright flue 38 is closed at its lower 55 end and open at its upper end and at an interval above the outlet tube of the radiator flue, a series of apertures 40 are provided at one or more sides of the upright flue which admit a certain amount of air to check a too 60 rapid flow of air from the radiator flue. A series of transverse baffles 41 may be provided in the radiator flue arranged alternately in the upper and lower part of the same, which serve to impede the flow of 65 flame from the burner, which may extend to

the outlet end of the flue for heating the same throughout its length.

One or more inclined inverted-channels 42 and 42' may be mounted over the end of the radiator flue above the heating element 70 thereinto, to deflect and direct the more highly heated air therefrom toward the other end of the cabinet; and above the discharge ends of these deflectors may be mounted a transverse deflecting plate 43 75 with a downwardly inclined flange 44 on its farther end, which serves to deflect the highly heated current of air directly toward the other end of the cavity of the cabinet.

A transverse screen 45 extending the entire length and width of the cabinet is preferably mounted immediately above the channel deflectors as by means of angle bars 46 resting upon angle brackets secured to the back and front walls of the cabinet; which screen prevents the clothing and other articles hanging in the cabinet from impinging the highly heated surfaces of the radiator flue and the deflectors.

The transverse deflector plate 43 is preferably slidably mounted upon the screen angle bars 46 as shown in Fig. 5, so that it may be adjusted longitudinally thereon for properly deflecting downward the heated air flowing from the inverted channels, so that the same will not impinge and discolor the articles hanging in the drier.

A plurality of tubular rack rods or bars 47 are longitudinally mounted in the upper part of the cabinet upon which the articles 100 to be dried therein may be hung, as shown in Fig. 1.

In the use of the cabinet, which is normally closed the gas burner or other heating element is placed in operation, and the heat therefrom creates a current of air passing through the radiator flue and thence up through the outlet flue 37. When a gas burner is used, a sufficient amount of air is drawn through the mixer 33 from outside 110 the cabinet to prepare the gas for combustion; but the air required for complete combustion is drawn into the radiator flue under the burner through the air tubes 35 from the vent chamber 25, which in turn draws air 115 through the apertures 36 in the top of the vent chamber from the interior of the cabinet, the air being drawn down from over and around the radiator flue and the inclined deflectors, at the end of the cabinet in which 120 the heating element is located.

A corresponding amount of air is drawn by the induced draft thus created, into the base through the apertures 22, and into the bottom of the cabinet through the apertures 125 23, located directly under the radiator flue, whence it impinges the bottom and passes around the sides of the radiator flue, and rises toward the top of the cabinet.

The incoming air thus rising is heated by 130

- the radiator flue throughout its length, but the more intensive heat created at the end of the flue containing the heating element creates a more rapid current around and above the same which is directed by the inclined deflectors 42 and 42' toward the other end of the cabinet, and may also be again directed downward by the deflector plate 43 so as to pass well toward the other end of the cabinet, whence it rises directly upward and thence across the top of the cabinet to the end above the heating element, whence the suction of the vent chamber carries the current directly downward; thereby creating a definite and certain circulation of the heated air upward in one end of the chamber and downward in the other end, so as to dry clothes or the like in all regions of the cabinet.
- 20 The outlet flue is made of a relatively large cross area so as to pass the volume of air, which is necessary or desirable for drying purposes; and the apertures in the wall of the flue check the flow of the air so that it does not move through the cabinet too rapidly for properly performing the drying process. The air received through the apertures also dilutes the gases of combustion and purifies the same before they are discharged from the flue.
- For this reason, it is not necessary to connect the outlet flue with a chimney or other conduit, but if it is desired to do so, the connection can be made by an extension 35 47 from the upper end of the shielding jacket 39, as shown in Fig. 4, and in this event the open lower end of this jacket, or apertures 48 provided in the extension therefrom, serve to prevent any excessive draft there 40 may be in the chimney, from unduly accelerating the circulating within the drier. The same openings also serve to prevent any down draft from the chimney, caused by atmospheric conditions, from affecting the proper 45 operation of the drier.
- I claim:
1. A drier for clothes and the like, including a normally closed cabinet, a longitudinal radiator flue therein adjacent to the bottom thereof, and means for causing a continuous circulation of air heated by the radiator, including deflecting means for directing the air toward one end of the cabinet and downward suction means for drawing the air in the other end thereof.
  2. A drier for clothes and the like, including a normally closed cabinet, a longitudinal radiator flue therein adjacent to the bottom and spaced from the sides thereof, a heating element in one end of the flue, a vent chamber under the same end of the radiator flue having apertures for receiving air from the interior of the cabinet and air tubes leading upward into one end of the radiator tube, there being inlet apertures in the bottom of the cabinet and an outlet at the other end of the radiator flue.
  3. A drier for clothes and the like, including a normally closed cabinet, a longitudinal radiator flue therein adjacent to the bottom and spaced from the sides thereof, a heating element in one end of the flue, openings in the radiator flue under the heating element for receiving air from the interior of the cabinet, there being air inlet apertures in the bottom of the cabinet under the radiator flue and an outlet at the end of the radiator remote from the heating element.
  4. A drier for clothes and the like, including a normally closed cabinet, a longitudinal radiator flue therein adjacent to the bottom and spaced from the sides thereof, a heating element in one end of the flue, there being openings in the radiator flue under the heating element for receiving air from the interior of the cabinet, air inlet apertures in the bottom of the cabinet under the radiator flue and an outlet at the end of the radiator flue remote from the heating element, and deflectors over the end of the flue containing the heating element for directing heated air currents toward the other end of the cabinet.
  5. A drier for clothes and the like, including a normally closed cabinet, a longitudinal radiator flue therein adjacent to the bottom thereof, a heating element in the radiator flue, there being openings in the radiator flue for receiving air from the interior of the cabinet and inlet apertures in the bottom of the cabinet, and an upright outlet flue leading from the radiator flue having apertures in its side for checking the flow of air from the cabinet.
  6. A drier for clothes and the like, including a normally closed cabinet, a longitudinal radiator flue therein adjacent to the bottom thereof, a heating element in one end of the radiator flue, baffles in the other end of the radiator flue, there being openings in the one end of the flue for receiving air from the interior of the cabinet and an outlet from the other end of the flue.
  7. A drier for clothes and the like, including a normally closed cabinet, a radiator flue therein adjacent to the bottom thereof, there being openings in the radiator flue for receiving air from the interior of the cabinet and apertures in the bottom of the cabinet under the radiator flue.
  8. A drier for clothes and the like including a drier cabinet, an outlet flue leading therefrom and a chimney connection leading from the outlet flue having openings to prevent the chimney draft from unduly accelerating the circulation within the drier.

JOHN S. SHANKS.
